UNITED STATES PATENT OFFICE.

ORSON W. BENNETT, OF WASHINGTON, DISTRICT OF COLUMBIA.

PRESSURE-REGULATOR FOR GAS-MACHINES.

SPECIFICATION forming part of Letters Patent No. 380,273, dated March 27, 1883.

Application filed August 4, 1887. Serial No. 246,149. (No model.)

To all whom it may concern:

Be it known that I, ORSON W. BENNETT, a citizen of the United States, residing at Washington, in the District of Columbia, have invented new and useful Improvements in Pressure-Regulators for Gas-Machines, of which the following is a specification.

I have improved the pressure-regulator for gas in which a flexible diaphragm is employed 10 with a valve for insuring the transmission of a uniform flow of gas of a determined pressure to the burners; and the objects of my improvements are to provide for increasing the durability of the diaphragm, to provide a cover for 15 preventing the evaporation of the lubricant for the diaphragm, and to increase the efficiency and durability of construction. These objects I attain in the manner which I will now proceed to describe, reference being had 20 to the accompanying drawings, in which—

Figure 1 exhibits a vertical section of my improved gas-regulator. Fig. 2 shows a modification of the same.

The diaphragm-containing chamber may be 25 of any suitable form and size; but I prefer to have the casing *a* made with a removable top section, *b*, for convenient access to the diaphragm.

The base-section *c* is provided with a central inlet-coupling, *d*, for connection with the meter outlet-pipe *d'*, and an outlet chamber or pipe, *e*, for connection with the burner-pipes, while the pressure-chamber forming section *f* has the flexible diaphragm *g* confined to its 35 bottom plate centrally over the inlet between vertical plates *g'*, so as to permit it to rise and fall with its valve *h*, the stem of which is connected centrally with said diaphragm.

The valve is preferably of conical form and has its 40 seat *i* in the inlet-coupling *d*, which is also provided with a guide, *j*, for the stem. The valve-stem passes through the diaphragm to receive the loading weights *k*, for obtaining a balancing adjustment of the valve. The diaphragm 45 is clamped to the valve-stem by plates *m*, and has a vertical movement to permit the seating of the valve should the pressure of the gas become great enough.

The inlet-coupling has a vertical tubular extension, *n*, which passes up through the out-

let-pipe and enters the pressure-chamber *f*, so as to form a curb around the inlet-opening above the valve-seat, and thus collect the tar and moisture within the outlet-pipe above the valve, so that the action of the latter cannot 55 become clogged and interfered with by surface collections or the drippings of tar sediment upon the valve-seat walls.

Around the fixed edge and exterior to the diaphragm is an annular receptacle, *r*, for a 60 lubricant for the diaphragm, which is thereby kept in a soft flexible condition. This lubricant need not entirely cover the diaphragm, because the latter will absorb it by capillary attraction, and thereby prevent the bad effects resulting from drying and cracking. I provide a further protection for the diaphragm by means of a cover, *s*, which dips into and is sealed in the lubricant and excludes the direct contact of the air. This cover may be stiff, as 65 in Fig. 1, or flexible, as in Fig. 2, the latter construction giving the advantage of being free to rise and fall with the valve, the stem of which may or may not pass through it. In Fig. 1 the valve stem passes up through said 70 sealing-cover and rises and falls with the valve independent of said cover. This sealing-cover permits the top case section to be removed to replenish the lubricant without exposing the diaphragm to the direct contact of the atmosphere, and, in connection with the lubricant, preserves the diaphragm in soft condition for 75 easy movement with the valve. As in Fig. 1, the cover also forms a seal for the lubricant and prevents it from evaporating and drying, 80 so that its replenishment is less frequent. This sealing-cover is independent of the diaphragm, 85 as shown in the drawings.

In practice I found that the unsteady and flickering light was effectually overcome by 90 providing the valve-stem or the diaphragm with a weight, *k'*, placed at one side of said stem, so as to exert a downward canting pressure upon the valve-stem or upon the diaphragm at a point near the circumference of the 95 latter, so as to tend to cant or tilt the valve-stem or its connected diaphragm. For this purpose the loading of the valve may be by a crank-arm, *u*, outside of the sealing-cover, or by weights centrally placed upon the valve- 100

stem and upon the diaphragm at one side of its valve-stem.

The tar-chamber *c* is formed below the pressure-chamber, so that the collection of moisture therein drips down into said chamber, from whence it may be removed by a plug, *t*; and were it not for this provision the valve would soon become coated and clogged with a resinous deposit.

10 As a lubricant I prefer to use glycerine, and when the diaphragm-cover is used also as a cover for the lubricant it forms a cover for the annular space *r*, as shown in Fig. 1.

The diaphragm is re-enforced by the usual 15 clamp-plates for attachment to the valve-stem, while the plates for confining it to the bottom of the case are made of unequal height, the inner one being of the greatest height and turned out to present a rounded surface to the leather 20 and form a groove, *w*, to retain any lubricant that may pass through or under the lower edge of the diaphragm.

I prefer to prepare the diaphragm with some 25 penetrating softening material to render it impervious—such as a compound of tallow, neat's-foot oil, and glycerine—and it may be coated with bronze-powder to protect the leather and render it impervious to gas.

It will be understood that the tar and moisture 30 gathers in the pipes leading to the burners, and

will run down into the chamber *c* and be confined therein by the guard *n*, over which the gas passes to the pipe *e*.

I claim—

1. In a gas-pressure regulator, the combination of a flexible diaphragm, a sealing-fluid, and a cover for the latter, covering also the diaphragm sealed by said fluid, as set forth. 35

2. In a pressure-regulator, the chamber forming case *a b*, containing a sealing-fluid, a flexible diaphragm forming the pressure-chamber, and a sealing-cover placed around and independent of the diaphragm, substantially as described, for the purpose specified. 40

3. A pressure-regulator for gas, consisting 45 of a flexible diaphragm forming a pressure-chamber, a sealing-fluid, a valve connected with and controlled by said diaphragm, a protecting-covering for said diaphragm, and an inclosing-case having the valve-controlled inlet, and an outlet having a tar and moisture collecting trap, all arranged as shown and described. 50

In testimony whereof I have hereunto set my hand in the presence of two subscribing witnesses. 55

ORSON W. BENNETT.
